UNITED STATES PATENT OFFICE.

JOHN J. SCHILLINGER, OF NEW YORK, N. Y.

BUILDING-BLOCK.

SPECIFICATION forming part of Letters Patent No. 293,524, dated February 12, 1884.

Application filed November 15, 1883. (No model.)

To all whom it may concern:

Be it known that I, JOHN J. SCHILLINGER, a citizen of the United States, residing at New York, in the county and State of New York, 5 have invented new and useful Improvements in Building-Blocks, of which the following is a specification.

My invention relates especially to blocks for the partition-walls of buildings, and particularly hollow blocks, also known as "hollow tiles." Heretofore the sides of these blocks have been made solid, and, due to the nature of the material composing the blocks, it is very difficult, if not impossible, to drive a nail for 15 hanging pictures or other purposes into the partition-walls to a greater depth than the plaster.

To overcome this defect is the primary object of my invention which therefore consists 20 in providing one or both sides of the blocks with nail-holes, such holes tapering in an inward direction, to more readily admit the nails and afford a superior hold thereto, as herein-after more fully set forth.

25 In the accompanying drawings, Figure 1 shows a block in cross-section embodying my invention. Fig. 2 is a side view thereof. Fig. 3 shows a modification.

Similar letters indicate corresponding parts.

30 The letter A designates the body of the block, which in this example is hollow, and in the sides of which are nail-holes B, tapering in an inward direction. These holes B are distributed over the entire area of the 35 sides of the block in close proximity to each other, so that a nail driven into the partition-wall of the building will generally meet a hole, sufficient space being, however, left between the holes to give the block the proper strength.

40 The largest and smallest diameters of the nail-holes B are respectively greater and less than the thickness of a nail, such as is commonly

used for hanging pictures, or fastening the base-boards or other carpenters' trimmings, and consequently either of the holes readily admits 45 the nail, while it has a tendency to bind the nail, thus affording a firm hold thereto. When the block is hollow, the nail-holes B pass entirely through the walls thereof, as shown in Fig. 1, and hence the nail also is allowed to 50 pass through either of such walls, it passing through the small part of the proper hole, and thus obtaining its hold in the block. The nail-holes B, however, may be of the same diameter throughout, inasmuch as the plaster of the 55 wall entering and filling the holes affords a hold to the nail, another effect of such condition of the plaster being to promote its adhesion. The nail-holes, moreover, may be either round 60 or square, as indicated in Fig. 2, and, if desirable, they may be continued in a straight line inward from the smallest part, as shown in Fig. 3.

What I claim as new, and desire to secure 65 by Letters Patent, is—

1. A building-block having one or both sides provided with nail-holes, substantially as shown and described.

2. A building-block having one or both sides provided with nail-holes tapering in an 70 inward direction, substantially as shown and described.

3. A hollow building-block having one or both sides provided with nail-holes tapering in an inward direction and passing entirely 75 through the walls of the block, substantially as shown and described.

In testimony whereof I have hereunto set my hand and seal in the presence of two subscribing witnesses.

JOHN J. SCHILLINGER. [L. S.]
